UNITED STATES PATENT OFFICE.

DAVID E. CROUSE, OF ANNAPOLIS, MARYLAND, ASSIGNOR TO THE AUTO AIR APPLI-
ANCE COMPANY, OF BALTIMORE, MARYLAND, A CORPORATION OF MARYLAND.

STARTING DEVICE FOR INTERNAL-COMBUSTION ENGINES.

1,090,600.

Specification of Letters Patent. Patented Mar. 17, 1914.

Application filed April 5, 1912. Serial No. 688,584.

To all whom it may concern:

Be it known that I, DAVID E. CROUSE, a citizen of the United States, and a resident of Annapolis, in the county of Anne Arundel and State of Maryland, have made certain new and useful Improvements in Starting Devices for Internal-Combustion Engines, of which the following is a specification.

10 My invention relates to improvements in starting devices for internal combustion engines, and it consists in the constructions, combinations, and arrangements herein described and claimed.

15 The device described herein is an improvement over that set forth in a prior Patent No. 1,036,972, August 27, 1912.

An object of the present invention is to provide a device which may be started from 20 any point by the mere compressing of an electric push button, the subsequent operation of the device serving to start the internal combustion engine and to restore the starting mechanism to its normal position.

25 A further object of my invention is to provide a pinion and a yielding rack member for engagement therewith, which will prevent a jerk or jar of the rack support when the engine starts up suddenly.

30 A further object of my invention is to provide means for withdrawing the rack from engagement with the pinion immediately on the starting of the engine.

Other objects and advantages will appear 35 in the following specification, and the novel features of the invention will be particularly pointed out in the appended claims.

My invention is illustrated in the accompanying drawings forming part of this application in which—

Figure 1 is a sectional view through the device showing the rack in its normal position, Fig. 2 is an end view of the device, Fig. 3 is a sectional view, showing the circuit breaking device carried by the rack, Fig. 4 is a sectional view showing the cam member for forcing the rack toward the pinion, Fig. 5 is a detail view of a portion of the rack when in engagement with the pinion, Fig. 6 is a side view of the device showing the rack at the end of its stroke, Fig. 7 is a section along the line 7—7 of Fig. 6, and Fig. 8 is a diagrammatic view of the circuit connections.

In carrying out my invention I provide a main cylinder 1 having therein a piston 2. The piston rod 3 is hollow. It extends through the upper end of the cylinder, is bent at 3^a and 3^b, and connects with the support 4 of the rack frame. The latter is provided with a passage 5 for establishing communication with the interior of the rack cylinder 6, which is carried by the member 4, and which is provided with a piston 7. The latter is always under the pressure of a spring 8.

The rack itself consists of two portions—a base portion 9 and a slidable portion 10, the latter being dovetailed so as to slide within the portion 9, as shown in Fig. 2. 70 The lower end of the member 9 is provided with laterally extending brackets 9^a and 9^b. A contact pin has a portion 11^a arranged to slide through the bracket 9^b and is provided with a reduced portion 11^b arranged to 75 slide in the bracket 9^a, as shown in Fig. 3. A contact 13 is provided and a spring 12 normally holds the reduced portion 11^b away from the contact 13. In Fig. 1, it will be seen that the rack rests directly on 80 the portion 11^a of the pin, but the spring is designed to be strong enough to separate the contacts 11^b and 13 unless the rack member 10 suddenly comes into contact with the portion 11^a of the pin in a manner explained 85 later.

The rack is carried upon a frame consisting of the end members 14 and 15, and the connecting member 16. The members 14 and 15 pass through the support 4 and 90 slidably support the rack. Secured to the cylinder 1 is a bracket 17 in which is pivotally mounted a cam member 18. This cam member is normally held by a spring 19 against a stop 20. It is designed to be engaged by a pin 21 on the rack member 9, so as to push the rack toward the pinion when moving in one direction, but to be pushed out of the way by the pin 21 when it returns. At one end of the cylinder 1 is 95 a magnetically controlled valve. This consists of a solenoid 22 having a core 23 provided at one end with a conducting arm 24 which is insulated from the core 23, but which is adapted to effect the closure of a locking circuit as will be hereinafter described. Secured to the opposite end of the core 23 is a valve 25 and a second valve

26. The first named valve is designed to establish communication between the pipe 27 and an exhaust opening 28, while the latter controls communication between the inlet pipe 29 and the pipe 27. Near the lower end of the cylinder 1 is a safety device consisting of a small cylinder 30 having a valve 31 disposed therein which is normally held closed by a spring 32. The valve 31 is connected with a contact member 33, which is normally in engagement with the contacts 34 and 35 at its ends. The support 4 is carried by brackets 36 and 37 secured to the cylinder 1, as will be seen from Fig. 2. The circuit connections are shown in Fig. 8. In this figure B is a battery and K is a push button. The conductor 24 is arranged to engage contacts 38 and 39. It will be seen that the contacts 11^b—13 and 40—41 are connected in parallel. The contacts 38, 34, 35 are also in circuit.

From the foregoing description of the various parts of the device, the operation thereof may be readily understood. The normal position of the apparatus is that shown in Fig. 1. In this position the rack is out of alignment with the pinion. The push button K is momentarily closed and current energizes the solenoid 22 over the following path: from battery B, through 42, K, 22, 43, 40, 41, 44, 35, 33, 34, back to battery. The movement of the solenoid brings the conducting arm 24 into engagement with the contacts 38 and 39, thereby effecting a locking circuit around the button K as follows: conductor 45, 39, 24, 38, 46, and back to battery over the remainder of the circuit just traced. The magnet 22 will therefore remain energized until the circuit is broken at some point. The inlet pipe 29 is designed to be connected with a source of compressed air (not shown) and the movement of the valve 26, due to the energization of the solenoid 22 will connect the pipe 29 with the pipe 27, thereby permitting the air to enter the cylinder 1. It will be observed that the valve 25 is closed at the same time that the valve 26 is opened. The air now passes through the hollow piston 3 and the passage 5 and pushes the piston 7 in the cylinder 6 outwardly. The rack member 9 however is attached to the rod of the piston 7 and hence the whole rack is moved bodily into alignment with the pinion 47. As the air continues to enter the pipe 27 the piston 2 will now be moved upwardly carrying with it the rack frame. At the first movement of the rack frame the pin 21 will engage the cam member 18, and will tend to assist the rack in its outward movement toward the piston. It will be noted that the contact 40 is elongated, so as to remain in engagement with the contact 41 until the teeth of the rack have engaged the teeth of the pinion. When this occurs the slideable

rack member 10 will be forced downwardly against the tension of the spring 12, thereby bringing into engagement the contacts 11^b and 13. The circuit of the solenoid 22 will therefore be completed through these contacts after the contact 40 leaves the contact 41. The upward movement of the rack will cause the turning of the pinion and the consequent starting of the engine. As soon as the engine picks up, the movement of the pinion in the direction in which the rack is moving will tend to relieve the tension on the spring 12 and the circuit therefore will be broken at the contacts 11^b—13. The teeth of the rack 10 are curved on one side and the engagement of the teeth of the pinion will tend to force the rack outwardly.

As soon as the circuit is broken the solenoid will release the contacts 38, 24, 39 and will cause the valve 25 to open and the valve 26 to close. This will let out the compressed air within the cylinders 1 and 6. The spring 8 within the cylinder 6 will press the rack frame away from the pinion, and the weight of the rack and the piston 2 will cause the latter to descend, the air passing out through openings, such as that shown at 28. As soon as the piston 2 reaches the bottom of the cylinder 1 the contact 40 will be in engagement with the contact 41, so that whenever the push button K is operated the apparatus will go through the operation just described.

From this description it will be seen that the rack is in engagement with the teeth of the pinion only long enough to start the engine and that immediately on the starting of the engine the rack will leave the pinion. This action, as stated before, is partly caused by the engagement of the pinion with the curved portion of the rack teeth and partly by the spring 8, which pushes the piston 7 before it as the air is exhausted. When the pin 21 engages the cam member 18 on its downward movement, the latter is pushed aside and springs into place again when the pin has passed it. In case there should be a "back fire" which would drive the pinion in the opposite direction the pressure inside the cylinder 1 would at once become very great. Normally the spring 32 in the safety cylinder 30 keeps the valve 31 on its seat against the pressure of the air, but where an excess pressure comes, as for instance in the reversal of the engine, the pressure will force the valve 31 outwardly, thereby permitting an escape of air through the opening 30 and at the same time breaking the circuit by the movement of the contact 33 out of engagement with the contacts 34 and 35 when the rack will be withdrawn from the pinion in the manner described.

The convenience of having only to press a button, I regard as an important feature of my invention, since this button can be placed anywhere on a vehicle, such as an au-

tomobile, and does not have to be placed among the numerous levers in front of the operator.

I claim:

- 5 1. In a device for starting internal combustion engines, a gear on the engine shaft, a rack normally out of alinement with said gear, said rack comprising two portions movable with respect to one another, means for moving said rack into alinement with said gear, means for moving the rack into engagement with the gear, an electrical circuit for controlling each of said rack moving means, and contacts carried by the rack 10 and forming part of the electrical circuit, said contacts being arranged to be separated by the movement of one of said rack portions relatively to the other rack portion thereby breaking the circuit.
- 15 2. In a device for starting internal combustion engines, a rack, said rack comprising a support, a slidable member carried by said support and provided with teeth, a pair of contacts carried by said support, one 20 of said contact members being arranged to be engaged by the toothed portion of the rack, a spring for holding said contacts normally out of engagement, means for moving the rack into alinement with the pinion, means for moving the rack into engagement with the pinion, the engagement of the rack with the pinion serving to force the contacts together against the tension of the 25 spring.
- 30 3. In a device for starting internal combustion engines, a gear on the engine shaft, a rack normally out of alinement with said gear, means for moving the rack into alinement with said gear, means for moving the rack into engagement with the gear, magnetic controlling means for each of said rack moving means, a source of current, a pair of contacts, one of said contacts being carried by said rack, connections between said 35 40 45 50 55 60 65 70 75 80 85 90 95 100 rack and said source of current, said contacts and said magnetic controlling means, the movement of said rack serving to separate said contacts, and a second pair of contacts in multiple with said first named contacts, the engagement of the rack with the pinion serving to close said second pair of contacts.
- 50 4. In a device for starting internal combustion engines, a gear on the engine shaft, a rack normally out of alinement with said gear, a piston for moving said rack into alinement with said gear, a second piston for moving the rack into engagement with the gear, auxiliary means for moving the rack into alinement with the gear, said auxiliary means comprising a spring controlled pivoted cam member, a pin carried by the rack and arranged to engage said cam member, and means for holding the cam member rigid during the engagement of the pin on one side of said cam member.
- 55 6. In a device for starting internal combustion engines, a gear on the engine shaft, a rack normally out of alinement with said gear, pneumatic means for moving the rack into alinement with the gear, pneumatic means including a cylinder and a piston for moving the rack into engagement with the gear, spring means for again moving the rack out of alinement with the gear, magnetic means for controlling the pneumatic means, an energizing circuit for said magnetic means, a spring-pressed plunger arranged to be operated by abnormal pressure within said cylinder, and normally closed contacts in said energizing circuit arranged to be broken by the movement of said plunger.
- 70 7. In a device for starting internal combustion engines, a gear on the engine shaft, a rack normally out of alinement with said gear, pneumatic means for moving the rack into alinement with the gear, pneumatic means including a cylinder and a piston for moving the rack into engagement with the gear, spring means for again moving the rack out of alinement with the gear, magnetic means for controlling the pneumatic means, an energizing circuit for said magnetic means, a spring-pressed valve carried by said cylinder and arranged to open under abnormal pressure within the cylinder to relieve such abnormal pressure, normally closed contacts in said energizing circuit, and connections between said valve and said last-named contacts for breaking the latter on the movement of the valve.
